UNITED STATES PATENT OFFICE.

CHARLES F. GILLET, OF SPRINGFIELD, ILLINOIS.

RUBBER OVERSHOE.

SPECIFICATION forming part of Letters Patent No. 280,603, dated July 3, 1883.

Application filed April 11, 1883. (No model.)

To all whom it may concern:

Be it known that I, CHARLES F. GILLET, of Springfield, in the county of Sangamon, and in the State of Illinois, have invented certain new and useful Improvements in Overshoes; and I do hereby declare that the following is a full, clear, and exact description thereof, reference being had to the accompanying drawings, making a part of this specification, in 5 to which—

Figure 1 is a perspective view of my improved shoe as preferably constructed; and Fig. 2 is a like view of the same, showing a slight change in the position of the elastic 15 gore.

Letters of like name and kind refer to like parts in each of the figures.

The design of my invention is to cause india-rubber overshoes to conform more perfectly to the feet of their wearer, and to be firmly held thereon, while capable of being easily placed over or removed from the feet; and to this end said invention consists in an overshoe having its counter above the heel 20 drawn forward to embrace the rear portion of the ankle, and provided within each side with an elastic gore, substantially as and for the purpose hereinafter specified.

In the use of rubber overshoes much difficulty has heretofore been experienced in causing the shoes to adhere sufficiently to the feet to prevent them from being removed while passing through mud, and many devices have been employed and various constructions of the shoes used for the purpose of overcoming 30 such objections.

In my shoe A the fore part has any usual form; but at its back end the counter a , above the heel a' , is drawn forward, as shown, so as 40 to cause it to closely embrace the rear side of the ankle of its wearer and to prevent said end from being readily drawn downward from the foot. At some point between the counter a and the instep portion a' a V-shaped gore, a^3 , 45 formed of pure rubber, rubber webbing, or other elastic material, is inserted within each

side of said shoe A, and has its edges connected therewith in any well-known manner, the object sought being to render practicable the elongation of said sides to enable the upper 50 portion of said counter to be drawn rearward and upward sufficiently to permit of the placing in or removal from position of said shoe. As the gore a^3 is arranged in Fig. 1, the line of draft extends from the upper portion of the 55 counter a to the shank a' , immediately in front of the heel a' , as shown by line x x of said figure, and causes no unusual strain to be thrown upon the front portion of the shoe; but by slightly changing the location of said gore, as 60 seen in Fig. 2, the line of draft may be caused to extend from the upper portion of said counter to the toe of said shoe, as shown by line z z of said last-named figure. By use of the elastic gores a^3 it thus becomes practicable to 65 draw forward the counter a to any desired point necessary to cause the shoe to adhere firmly to the foot of the wearer, while without said gores any appreciable drawing forward of said counter renders very difficult the putting 70 on or removal of the shoes, and it is impracticable to use the latter when said counter has been drawn forward sufficiently to cause it to afford any protection against accidental displacement.

Having thus fully set forth the nature and merits of my invention, what I claim as new is—

A rubber overshoe having its counter above the heel inclined forward to embrace the rear portion of the ankle, and provided on each side with an elastic gore adapted to keep the counter normally drawn forward into its inclined position, substantially as and for the purpose specified.

In testimony that I claim the foregoing I have hereunto set my hand this 2d day of April, 1883.

CHARLES F. GILLET.
